Primary Examiner—Prabhakar G. Deshmukh
Attorney, Agent, or Firm—John L. Welch**[57] CLAIM**

The ornamental design for a transparent package for candle and holder, as shown and described.

DESCRIPTION

FIG. 1 is a side elevational view of the transparent package for candle and holder according to my invention, the other three side view being identical;

FIG. 2 is a top plan view thereof;

FIG. 3 is a bottom plan view thereof; and,

FIG. 4 is a sectional view thereof, taken along the lines 4—4 of FIG. 3.

The broken line showing of a candle and holder is for illustrative purposes and forms no part of the claimed design.

FIG. 1

FIG. 2

FIG. 3

FIG. 4
